UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,119,966.

Specification of Letters Patent.

Patented Dec. 8, 1914.

Application filed April 28, 1911. Serial No. 623,905.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to electric switches.

One object of my invention is to provide a simple, compact and durable switch wherein the actuating member or members may 15 be disposed at any desired angle to the line of movement required of the means directly operating the switch mechanism.

A further object of my invention is to eliminate the necessity of using levers and 20 other complicated means for causing reverse movement of the operating members of the switch where such movement is desired as for example in flush switches.

Various other objects and advantages of 25 my invention will be hereinafter set forth.

In the application I shall describe my invention as applied to a push button flush switch, but I have chosen this type only as a means of illustrating the principle of my 30 invention which is capable of being used with various other types of switches and in various other relations.

In the accompanying drawings I have, for 35 purposes of illustration, shown two forms which my invention may assume in practice when applied to a switch of this type. Of course my invention may be embodied in various other forms.

The views in the drawing are as fol- 40 lows:

Figure 1 shows a top plan view of a switch. Fig. 2 shows a partial central sectional view. Fig. 3 shows a sectional view on line 3-3 of Fig. 2. Fig. 4 shows a de- 45 tail view of the switch operating mechanism, portions thereof being shown in section. Fig. 5 shows a partial sectional view of a portion of the switch operating mechanism. Fig. 6 shows a perspective view of one form 50 of movable contact. Fig. 7 shows an enlarged partial sectional view of the cam member and the spring. Fig. 8 shows a bottom plan view of the switch casing. Fig.

9 shows a top plan view of an improved form of switch with the finishing cover removed. Fig. 10 shows a partial sectional view through the complete switch shown in Fig. 9. Fig. 11 shows an enlarged perspective view of a modified form of movable contact member. Fig. 12 shows an enlarged detail view of a portion of the switch shown in Figs. 9 and 10.

Let us first consider the construction shown in Figs. 1 to 8 of the drawings. In Fig. 2 I have illustrated my improved 65 switch mechanism inclosed in a substantially rectangular shaped two-part casing. This casing may be of any suitable insulating material such as porcelain, for example, and may consist of an upper portion 1 and a 70 lower portion 2. These portions 1 and 2 are adapted to be clamped together and are provided with intercommunicating recesses in their adjacent faces adapted to house the switch mechanism. In a preferred form I 75 bind the two parts of the casing together by the terminal connections 3. These terminal connections 3 preferably have flat upper ends suitably fixed to the top of the casing near the corners of the same as by contact 80 screws 4 and have downwardly extending portions 5 preferably of a rectangular cross-section, which pass vertically downward through the two-part casing to the bottom surface of the lower part 2 of the casing. 85 See Fig. 8. In a preferred form the lower ends of these contact parts 5 are screw-threaded and fitted with taps 6 which serve to clamp the parts of the base securely together to form a unitary structure. As 90 shown in Figs. 2 and 8, I preferably provide an insulating strip 7 between the taps 6 and the lower surface of the casing. In a preferred form I also provide means consisting of inwardly extending shoulders 8 95 on the casing members which act to guide and strengthen the contact members 5 as they pass down through the casing. See Fig. 3. By this improved construction I am able to hold the parts of the casing together 100 by the terminal connections for the switch and thus do away with unnecessary parts.

The switch mechanism proper is housed between the two parts 1 and 2 of the casing and includes a cam member 9 in the form of 105 a double frustum, the frustums being posi-

tioned base to base so that the cam 9 has an enlarged center portion from which tapering portions extend to each side toward the longitudinal axis of the cam member. The cam member is shown in Figs. 2 and 5 and is preferably constructed of sheet metal and provided with flanges 10 at the outer ends thereof. The cam is provided with a center supporting member 11, semi-cylindrical in cross-section and preferably constructed of sheet metal as shown in Fig. 7. The supporting member 11 has upwardly extending portions 12 preferably struck up at the ends thereof, which are adapted to be secured to the cam member 9 as by passing through apertures 13 formed in the ends of the latter. The member 11 also has an inwardly extending tongue 14 located at about its middle portion which is adapted to extend between the adjoining helices of a spring operating member 15. (Fig. 4). This spring operating member 15 extends through the semi-cylindrical member 11 and in a preferred form the inwardly extending projection 14 engages the spring member 15 at about its middle point. The spring member 15 is guided in its movement by a member 16, preferably semi-cylindrical in cross-section throughout the greater portion of its length and adapted to unite with the semi-cylindrical member 11 to form a cylindrical casing for the spring member 15. In a preferred form the member 16 is also made of stamped metal and is provided with upturned ends 17. These upturned ends 17 are of a cylindrical cross-section and are held in place in the casing 2 by transverse strips 18. At points adjacent and above these ends 17, the spring member 15 is suitably fixed to push buttons 19 and 20 as by having its opposite ends inserted in the same as shown in Fig. 4. These push buttons 19 and 20 are preferably composed of insulating material and are of the usual conformation at the tops, but are provided with downwardly extending portions 21 and annular shoulders 22 at about their middle points. These downwardly extending portions 21 move in recesses 23 in the casing and act as guides for the push buttons, while the shoulders 22 abut against the edges of perforations 24 formed in an insulating plate 25 extending across the open face of the casing, to limit the movement of the push buttons 19 and 20 and prevent these push buttons from being moved too far out of the casing. This insulating plate 25 may be held in engagement with the upper portion 1 of the casing by centrally located screws 26 and may be fixed to a wall or other surface by screws 27 located near its ends. An outer finishing or surface plate 28 is preferably fixed to the insulating plate 25 by screws 28a and is provided with perforations registering with the perforations 24

in the insulating plate 25. By the use of this insulating guiding plate, I am able to locate the parts very accurately since this plate may be very accurately perforated or stamped.

In a preferred form the cam member 9 is engaged by a resilient member in the form of a helical spring 29 which has its ends secured together as shown in Fig. 7, to form a ring which entirely surrounds the cam member. The cam and spring are so arranged and co-act in such a manner that by reason of their construction and the pressure between them, movement of one along the engaging surface of the other, is secured when the push button is operated, which movement takes place at an accelerated speed and independent of the operating means. The cam 9 is moved by the push button into a predetermined relation with respect to the spring 29 or until this spring reaches the point where the two frustums forming the cam meet and then the spring moves automatically and independently of the cam and of the operating buttons to its other limit of travel.

In Fig. 6, I have shown one form of contact member adapted to be moved by the helical spring 29. This contact member comprises a body-portion 30 which is preferably formed of a single piece of metal bent at its center so that said body-portion is substantially U-shaped in cross-section. One side of the body-portion is preferably formed with extended ends 31 which are bent at right angles to the plane of said side and toward the other side. The ends 31 when thus formed provide means whereby contact engaging portions 32 and 33 may be secured in alignment with each other on the opposite ends of said body-portion 30. Corresponding apertures 34 are formed centrally in the sides of the body-portion 30 of just sufficient size to allow the passage of the cam 9 therethrough. In assembling the contact member 30, and the cam 9, the spring 29 is disposed in the base between the sides of said contact member 30 and the cam member 9 is inserted through the apertures 34 in the sides thereof, and through the spring.

In Fig. 3, I have shown a section through the complete switch. When it is desired to move the contact member 30 to its opposite limit of travel from that shown, one of the buttons 19 and 20 is moved downward, thus causing the spring 15 to slide along within the guiding member 16 and move the cam member 9 fixed to the spring through the supporting member 11, through the contact member 30 and the helical spring 29 therein, until the center portion of the cam 9 passes through said spring 29. After passing over this center portion of the cam, the helical spring 29 engages the oppositely inclined face of the cam, and due to its

having been tensioned, will be moved quickly to the opposite end of said cam member 9, thus carrying the contact member from one limit of its travel to the other with a quick 5 snap action. As illustrated in Fig. 3, the limits of its travel may be the terminal contacts 5. The contact member 30 moves in a plane at right angles to the contact surfaces of these terminal members 5, so that the 10 ends 32 and 33 of the member 30 will engage the same with a wiping or sliding action and with a minimum of sparking. It is, of course, to be understood however, that instead of the connection shown in Fig. 3, 15 the switch mechanism may be used to make or break a circuit in any desired manner, and that it may be used for controlling a single circuit, a pair of separate circuits or as a three way switch.

20 In Figs. 9 to 12, I have shown a modified form of the switch. In this modified construction I preferably form the supporting casing of one cup-shaped piece of insulating material 35. As in the case of the previous 25 construction, I employ an insulating guiding plate 36 suitably fixed to the upper surface of the casing and an outer face plate 37 suitably fixed to the guiding plate 36. Both of these plates are provided with suitable 30 perforations for the push buttons 38 and 39. In this construction I provide a supporting and guiding rod 40 for each end of the spring operating member 41. In a preferred form the upper ends of these 35 guiding rods 40 are slotted as shown at 42 in Fig. 12 and are adapted to engage flanges 43 formed in longitudinally disposed recesses 44 in the insulating plate 36 and be held by these flanges in the said recesses.

40 The push buttons 38 and 39 in this construction are preferably provided with lateral extensions 45 at their lower ends preferably provided with apertures 46 to fit over the guiding rods 40 and slide upon the 45 same. The opposite ends of the spring operating member 41 are preferably secured to these extensions 45 so that when the buttons are depressed, the extensions 45 will be moved downward to cause a bodily movement of the spring member 41, whereby the 50 cam will be moved and the switch mechanism operated. In this construction the cam member consists of an insulating sleeve 47 of substantially the same conformation as the sleeve 11. This sleeve 47 is fixed to the spring member 41 so as to move with the same by an inner sleeve 48 fitted between the spring member and the cam member 47 and preferably of a construction permitting 55 it to engage between the helices of the spring member 41. The action of this cam member is the same as that of the cam member 9 previously described.

In Fig. 11 I have shown a modified form 60 of movable contact member. This contact

member is formed of two plates 49 and 50 which are spaced apart and have inwardly extending portions 51 which are fastened together in any desired manner as by rivets 52. These plates may be insulated from 70 one another if desired. Each of these plates 49 and 50 has its opposite ends bent outwardly as shown in Fig. 11 to form parallel contact surfaces 53 on the opposite ends of the same. As in the case of the previous 75 construction, this contact member is provided with opposite perforations 54. Just as previously described, this contact member is adapted to inclose a helical spring 55 and move upon the cam member 47 when 80 the push buttons are operated. In this instance, however, instead of engaging terminal contacts of the conformation of the contacts 5 illustrated in Fig. 3, the movable contact member engages spring clip contacts 85 56 which are adapted to receive the ends of the contact surfaces 53 and are preferably formed of single pieces of material suitably fixed to binding screws 57, as illustrated in Fig. 9.

90 While I have shown and described in this application two specific forms which my invention may assume in practice, my invention itself is in no wise limited to these specific forms, but may assume other forms, 95 and be adapted to switches of various other types, all of which fall within the scope of my present improvement.

What I claim as new and desire to secure by Letters Patent is:—

1. In an electric switch, the combination with a longitudinally movable contact actuating member, of an operating member therefor movable longitudinally and at an angle thereto, longitudinally movable means 105 operatively connecting said members, and a guide for said connecting means intermediate said members.

2. In an electric switch, the combination with a longitudinally movable contact actuating member, of an operating member therefor movable longitudinally and at an angle thereto, a curvilinear guide between said members, and means movable longitudinally of said guide for operatively connecting said members.

3. In an electric switch, the combination with a longitudinally movable contact actuating member, of an operating member therefor movable longitudinally and at 120 right angles thereto, a fixed guide between said members, and means operatively connecting said members and movable longitudinally in a single path controlled by said guide.

4. In an electric switch, the combination, with a longitudinally movable contact actuating device, of an operating member therefor movable longitudinally at right angles thereto and a flexible thrust member be- 130

tween said device and said operating member.

5. In an electric switch, the combination, with a longitudinally movable contact actuating member, of an operating member therefor movable longitudinally at right angles thereto and a thrust connection between said members comprising a helical spring.

6. In an electric switch, in combination, 10 a movable contact actuating member, an operating member therefor movable in a direction at an angle thereto, a curved guide member arranged between said two first-mentioned members, and a single flexible member in said guide to transmit movement 15 of said operating member to said contact actuating member.

7. In an electric switch, the combination with a contact actuating member, of a longitudinally movable member having a flexible portion for transmitting the thrust thereof to said contact actuating member and a substantially right angle guide for 20 said flexible thrust portion between said members.

8. In an electric switch, the combination with a longitudinally movable operated member, of an operating member therefor movable longitudinally at right angles 25 thereto, a helical spring connecting said members and a curved guide for said helical spring between said members.

9. In a flush switch, the combination with a longitudinally movable operated member, 30 of a pair of push buttons therefor, movable at right angles thereto and flexible thrust connections between said push buttons and said operated member.

10. In a flush switch, the combination 35 with a longitudinally movable operated member, of a pair of push buttons for operating the same, said push buttons being movable at right angles to said operated member and a flexible member provided 40 with a substantially right angle guide, be-

tween each of said push buttons and said operated member.

11. In a flush switch, the combination with an operated member of a longitudinally movable flexible member connected 50 thereto and having its extremities disposed at right angles to its intermediate portion and push buttons connected to the extremities of said flexible member.

12. In a flush switch, the combination 55 with a longitudinally movable operated member, a helical spring connected thereto, guides for directing the extremities of said spring at right angles to the line of movement of said member and push buttons co-operating 60 with the extremities of said springs to thrust said operated member in opposite directions.

13. In an electric switch, in combination, 65 a reciprocable cam member, a contact member movable over said cam member, resilient means acted on by said cam member and acting on said contact member for moving the latter with a snap action, push buttons movable at right angles to said cam member 70 to reciprocate the same, and a single flexible member operatively connecting said push-buttons and said cam member.

14. In a flush switch, the combination with a longitudinally movable double frustum cam member, of a spring encircling the same and co-operating therewith to impart 75 a snap action to the switch contacts, a pair of push buttons movable at right angles to said cam member and a flexible member connecting each of said push buttons to said cam member and to the other push button.

In witness whereof, I have hereunto subscribed my name in the presence of two witnesses.

CHARLES J. KLEIN.
